UNITED STATES PATENT OFFICE.

FREEBORN F. RAYMOND, 2d, OF NEWTON, MASSACHUSETTS.

MACHINE FOR FEEDING AND ATTACHING RANDS TO BOOTS OR SHOES.

SPECIFICATION forming part of Letters Patent No. 408,895, dated August 13, 1889.

Application filed April 16, 1887. Serial No. 234,989. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Machines for Feeding and Attaching Rands to the Soles of Boots or Shoes, of which the following is a full, clear, and exact description, reference being had to the accompanying drawings, forming a part of this specification, in explaining its nature, in which—

Figure 1 represents in vertical section my improved machine. Fig. 2 is a view, part in horizontal section and part in plan, upon a line below the templet-plate and above the bed upon which the rand-former moves. Figs. 3, 4, and 5 represent in plan view portions of the welt forming and feeding device in various positions. Fig. 6 is a view illustrating the operation of the welt-pressure plate, to which reference is hereinafter made. Figs. 7, 8, and 9 show modified forms of the invention, to which reference will hereinafter be made. Fig. 10 is a view in elevation of a portion of the head of the machine. Fig. 11 is a detail view in vertical section taken through the templet. Fig. 12 is a perspective view of a part of the templet and rand-former inverted. Figs. 13, 14, and 15 are views of a shoe, illustrating the operation of the machine.

The object of the invention is to feed rands into position for attachment to the outsole of a boot or shoe to form it to the shape of the edge of the outsole at the heel end, and for attaching it to the outsole while thus held formed to the outsole, and subsequently to mold it under pressure, so as to cause it to be set down somewhat with the edge of the outsole in relation to the remainder of the sole at the heel-seat. The invention therefore involves a method and means for carrying it into effect.

45 The means which I have illustrated are represented in the drawings, as follows:

A represents a last or work-support. It is mounted upon a rod or support a , which is vertically movable in the jack-post a' . This 50 jack-post is mounted upon the slide-plate a^2 . The rod or support a is represented as made

vertically movable by means of the toggle-head a^3 , the toggle a^4 , lever a^5 , pivoted at a^6 and connected with the toggle by means of the link a^7 , and the cam a^8 on the vertical shaft a^9 , having a cam-groove a^{10} , which receives a cam-pin upon the end of the arm a^{11} of the lever a^5 .

B is a templet, preferably stationary, and which is provided with holes or perforations b , through which the rand-attaching nails are driven. This templet has a surface b' , which is flat or very slightly concave at its center, and which is beveled or cut away upon its sides and back, as at b^2 , substantially of the form of a rand, to provide a rand-former. (See Figs. 1 and 11.) This provides the templet with a section which is adapted to bear upon the surface of the outsole at the heel end thereof well within the edge of the sole, and which receives the upward pressure of the work-support A, and the templet is so fashioned or shaped outside this section b' upon its sides and back as to provide a recess between the upper surface of the outsole, when in place, and the inclined surface b^2 of the templet, which is of a shape to receive the rand. This inclined surface b^2 may be continuous from the flat surface b' backward and upward about the width of the rand used, or it may end against a narrow shoulder b^3 , as shown in Fig. 11.

Behind the last or work-support A is a post C, which is represented as vertically adjustable in its stand c by means of the screw c' and nut c^2 , and this post supports a table C' in two parts $c^3 c^4$. (See Fig. 7.) Each of these parts has a dovetailed tongue c^5 , Fig. 1, which extends into a dovetail recess cut across the upper surface of the post C, and the two sections $c^3 c^4$ are provided with movements toward and from each other by means of the right-and-left screw c^6 . Each of these sections $c^3 c^4$ of the table extends forward, and they are curved at $c^7 c^8$, respectively, to approximate the curve of the heel end of the outsole.

The object in making the table in two parts is to provide the opening C², bounded by the edges $c^7 c^8$, with adjustment as to size, in order that the table may be set closely to the heel-edge of an outsole of any size. The table

also acts to support the rand and direct its movement to the surface of the sole, so that its upper surface preferably should be set to be a trifle above the upper surface of the outsole. This table is covered by the templet and the templet plate or support, so that there is formed between its upper surface and the under surface of the templet-plate and templet a guiding space or recess, along which the rand may be moved while it is being fed to the templet-former.

To move the rand into position, I prefer to employ a flexible carrier and former D. (See Figs. 2, 3, 4, and 5.) This carrier and former may be made of rawhide or leather, or spring-steel, or of any other suitable material, and it is attached at each end to the ends d' of the levers d². These levers are pivoted, respectively, at d³ d⁴ to a sliding support or block d⁵, which is provided with a horizontal movement toward and from the templet by means of the cam-groove d⁶ in the cam-disk d⁷ upon the vertical shaft a⁹, the sliding support or block d⁵ having a cam-pin d⁸, which enters the cam-groove d⁶, and being guided in the frame of the machine in a suitable guide-way and held in place preferably by cap-plates. (See Fig. 2.) The levers d² are connected with the springs d⁹ d¹⁰, which keep the ends d' separated from each other and the flexible carrier D substantially taut and also straight, excepting while engaged in forming the rand about the former and upon the surface of the outsole.

In operation the rand is placed, preferably, in a slightly-tempered condition upon the table C' in front of the flexible carrier D, the boot or shoe mounted upon the last or work support, and the last or work-support moved into position to bring the rod or movable support a over the toggle-head a³ and the heel end of the outsole beneath the templet B. The machine is then set in operation. The cam a³ moves the work-support or last A upward and brings the heel end of the outsole in contact with the under surface of the templet. This is immediately followed by the forward movement of the slide-plate d⁵ and levers or arms d², which cause the rand-carrier to move the rand upon the table until its central section is moved between the templet-former and the upper surface of the outsole. (See Fig. 4.) The movement of the lever-support d⁵ continuing causes the rand to be turned about the former between the under surface of the templet and the outsole until the entire rand has been brought into shape—that is, curved to fit the outer edge of the heel-seat or heel end of the outsole—and the parts are then in the position shown in Fig. 5.

The cam for moving the levers d² to cause the rand to be fed and formed is timed to move it immediately at the end of the upward movement of the work-support, and this is followed by the immediate driving of the rand-attaching fastenings or nails. These fastenings are fed, preferably, automatically to the

holes b of the templet by a nail-carrier E, which is moved from a position in which it receives nails or fastenings from a nail or fastening making device (not shown) to a position to deliver them to the holes b by means of the cam e on the vertical shafts a⁹, which cam has the cam-groove e', which receives the pin e², extending upward from the plate e³, by which the nail or fastening carrier is secured, or at the end of which it is formed.

The cam e is timed to move the nail-carrier into position to deliver its fastenings or nails immediately after the completion of the feeding forward of the rand, so that there is immediately delivered to the holes of the templet the nails or fastenings for attaching the rand.

F is a gang or group of drivers carried by a plate f, supported by a head f'. This head f' is shown as moved by the cams f² f³, each of which has a cam-groove f⁴, and these cam-grooves receive the cam-pins f⁵, extending laterally from the head f'. The cams f² are carried upon the horizontal shaft f⁶, which has bearings at f⁷ in the bracket f⁸ and at f⁹ in the bracket f¹⁰, and there is attached to the back end of this shaft f⁶ a bevel-gear f¹¹, which meshes with the bevel-gear f¹² upon the upper end of the vertical shaft f⁹. The cams f² f³ are so timed as to move the drivers downward through the holes in the nail-carrier and templet to drive the nails from the templet immediately upon the movement of the carrier into position, so that immediately after the holes in the nail or fastening carrier register with the holes in the templet the drivers enter the holes and drive the fastenings into the rand and out sole or soles.

It will thus be seen that the various operations of the parts—namely, the upward movement of the last or work-support, the feeding and forming of the rand, the feeding of the rand-attaching nails, and the driving thereof—are successive automatic operations, and that they are all caused by cams, so that they can all take place at least in one complete rotation of the shaft a⁹, or upon any part of said rotation desired.

The fastenings or nails driven may not only be used for securing the rand to the sole or soles, but also for the purpose of securing the outsole, upper, and counter to the insole, thereby providing a very strong and rigid heel-seat. Immediately upon the driving of the fastenings the drivers are lifted from the templet and nail-carrier, and the nail-carrier is moved back to its original position to receive another load of nails or fastenings.

To flatten the rand upon the outsole, and also to mold the heel and outsole to some extent, so that the upper surface of the rand shall be made level or very nearly level with the surface of the sole inclosed by it, I use a pressure-plate G, (see Fig. 11,) which pressure-plate preferably forms part of the templet-plate, and is moved in suitable guides g from one side of the machine to move the templet out of position and to

bring the imperforate forming-surface G' , having any desired shape, over the last or work-support. It is moved into position after the driving of the rand-attaching nails or fastenings, and when this plate is used the cam a^8 is constructed so as to move the last or work-support A downward immediately upon the driving of said fastenings to permit the horizontal movement of said pressure-plate 5 into position, and then to immediately move the last or work-support with the shoe and the attached rand upward, so that the sole and attached rand are brought against the under surface thereof and pressed, molded, or flattened. This pressure-plate G is moved 10 into and out of position by means of the cam-groove g' in the under surface of the cam d^7 (see Figs. 1 and 6) and the lever g^2 , which is pivoted at g^3 , and which is connected at one end 15 with the said pressure-plate G and at the other end has a cam-pin g^4 , which enters the cam-groove g' , so that upon the rotation of the cam the plate is at the proper time moved into position and held there during the upward movement of the work-support and work in relation thereto, and then upon the downward movement of the work-support returned to its original position and held until it is again operated. After the driving of the 20 attaching nails or fastenings into the rand the rand-carrier D is immediately moved backward. At the end of its forward position the levers or arms d^2 , it will be seen, have been turned upon their centers, so that 25 their ends d^2 approach each other to cause the carrier D to press or draw the rand properly upon the templet-former. Of course this movement is in opposition to the stress of the springs d^9 d^{10} . Upon their backward movement they are moved to their original position by the springs—that is, they are caused to 30 assume the position in relation to each other shown in Figs. 2 and 3.

In Fig. 7, in lieu of a carrier supported by levers d^2 , I have shown the levers or arms d^2 as provided with jaws for grasping the ends of a rand to hold it during their feeding and forming movement, which is fully shown in detail perspective by Fig. 9. This holder or carrier I consider to be the equivalent of the carrier D, although it is not as desirable a form of construction.

In Fig. 8 I show the feeding and forming levers d^2 , provided with rolls at their inner ends and as hung in a somewhat different manner from that shown in Fig. 3, the ends of the lever being brought quite closely together, and the rolls being arranged to bear against the back edge or thick part of the 55 rand near the center of its length, and upon the forward movement of the levers the rand is pushed into the space between the upper surface of the outsole and the under surface of the templet at the back end of the heel, and this is about the center of the length of the rand, and from this point the rolls are caused by the advancing movement of the 60

levers to be separated and to press against the back edge of the rand with a gradually-advancing movement, and to thus turn each 70 section thereof into the recess between the outsole and the templet and about the former until the entire rand has been turned or brought to the desired shape. While considering this as an equivalent for that employing 75 the carrier D, yet it is not as desirable a construction. The vertical shaft a^9 preferably is rotated or turned by means of a worm-wheel H and arm h on the driving-shaft h'.

In operation the rand is first placed upon 80 the table C' in front of the rand feeding and forming devices. The boot or shoe is mounted upon the last or work-support and the jack moved into position beneath the templet. The machine is then started. The last or 85 work-support is moved upward to bring the heel end of the soles against the under surface of the templet B and is pressed against the same with any desired compression. This upward movement of the last or work-support is immediately followed by the forward movement of the rand feeding and forming devices and the fitting of the rand upon the templet-former to the outsole so that it is 90 in a position to be attached thereto by its 95 attaching nails or fastenings. The nails or fastenings are fed very nearly simultaneously with the feeding, forming, and fitting of the rand and delivered to the holes of the templet and driven by the immediate descent of 100 the drivers. The drivers are then immediately withdrawn, the nail-carrier moved backward to its original position, and the rand carrier and folding devices also returned to 105 their normal position, the last or work-support lowered, the compression-plate moved inward by its cam, the last or work-support again elevated by its cam, and the outsoles caused to be compressed and formed to any desired extent.

To properly prepare the heel-seat for the reception of the heel-blank, it is desirable that the surface thereof should be flat or very nearly flat. Consequently, this pressure in most instances acts to force the edge of the 115 outsole, the insole, and the rand downward upon the rounded edge of the last or work-support, so as to bring the surface of the rand substantially level with the part of the sole within its inner edge. In other words, this 120 compression molds the heel end of the soles and the rand.

Attaching nails or fastenings of a length sufficient to extend through the outsole, counter, upper, and insole may be used, in 125 which case the heel end of the outsole is not attached to the insole by sewing or nailing until the attachment of the rand, when this section of the outsole is simultaneously secured or fastened with the rand to the upper 130 and to the insole.

I would say that substantially the same devices can be used for attaching welts to outsoles.

Having thus fully described my invention, I claim and desire to secure by Letters Patent of the United States—

1. In a rand feeding and attaching machine, the combination, with a block or templet having a rand-forming surface, of a horizontally-movable rand carrier and former and a last or work-support for holding a boot or shoe with its outsole in approximate relation to said block or templet, substantially as described.
2. In a rand feeding and attaching machine, the combination of a templet having rand-forming surface and vertical apertures extending therethrough, the last or work-support for holding the heel end of the outsole on the boot or shoe in contact with the templet, a horizontal movable rand carrier and former for fitting the rand about the said forming-surface of the templet and on the surface of the outsole, and mechanism disposed above said parts for driving fastenings through the apertures in the templet into the rand, substantially as described.
3. In a rand feeding and attaching machine, a rand-feeding device, substantially as described, comprising two levers or arms mounted upon a block and adapted to be moved simultaneously, and the working or forming ends of which levers or arms are adapted to be moved away from each other, and which are arranged to draw or bear against the rand to move it into position about a former, as and for the purposes described.
4. The combination of the perforated rand former or templet B, adapted to bear against the outsole of a boot or shoe, a table having its edge extended about the edge of the heel end of the outsole and having its surface upon the same or substantially the same level as that of the outsole, a rand feeding and forming device comprising a flexible band or strap D, supported at each end by a yielding lever or arm, which lever or arm is provided with closing movements in relation to the former, as and for the purposes described.
5. The combination of the rand-carrier D, table C', rand-former b², levers d², slide d⁵, springs d⁹ d¹⁰, and the cam d⁷, having a cam-groove d⁸, for moving the slide, as and for the purposes specified.
6. The combination of the rand-former, the last or work-support, and the rand-table C', having an opening C², for the reception of the heel end of the outsole of the boot or shoe, the said table being made in separate parts, provided with mechanism, substantially as described, for moving them toward and from each other, whereby the size of said opening may be varied, as and for the purposes specified.
7. The combination of the table C', made in two parts c³ c⁴, each of which has a horizontal movement upon the post C, with a device for moving said plates horizontally upon said post to vary the relation of their edges

c⁷ and c⁸ in relation to each other, substantially as specified.

8. In a rand feeding and attaching machine, 70 the combination of the table C', having a surface upon which the rand-carrier and rand are moved and an opening which receives the heel end of the outsole, with a post or support C and means for vertically adjusting 75 said post, substantially as specified.

9. In a rand feeding and attaching machine, the combination of the perforated rand-former or templet, a vertically-movable last or work-support, a horizontally-movable rand carrier 80 and fitter, a horizontally-reciprocating nail or fastening carrier mounted over said former or templet, and driving mechanism disposed above said parts, substantially as described.

10. The rand-former having the bearing- 85 surfaces b' and the inclined forming-surface b², as and for the purposes described.

11. A combined rand-former and templet comprising a block B, having holes b, bearing-surfaces b', and the forming-surface b², 90 as and for the purposes described.

12. In a rand feeding and attaching machine, the combination, with a rand-former and a rand carrier and fitter coating with said former, of a movable sole-support adapted 95 to be operated toward and away from the aforesaid parts simultaneously with the movements thereof by mechanism relatively timed and connected to the same, substantially as described. 100

13. The combination of the templet B, having the holes b, the head f', the block f, carried thereby and supporting a gang or group of drivers F, the cam f², having a cam-groove which receives a pin-carrier by said head, the 105 shaft f⁶, the vertical shaft a⁹, and the bevel-gears f¹¹ f¹², substantially as described.

14. In a rand feeding and attaching machine, the combination of the slide-head f', supporting a gang or group of drivers, having 110 cam-pins f⁵, with the two cams f² f³, mounted upon the shaft f⁶ and having cam-grooves which receive the cam-pins carried by said head and said shaft, substantially as described.

15. In a rand feeding and attaching machine, the combination, with a templet, of the rand carrier and fitter, the cam having a groove g', and the lever g², pivoted at g³, substantially as and for the purpose set forth. 115

16. The combination, in a rand-attaching machine, of a movable work-support A, a templet B, having a rand-forming surface b², a nail-carrier E, a reciprocating gang or group of drivers, and a rand feeder and fitter, 120 as and for the purposes specified.

17. In a rand feeding and attaching machine, the combination of a movable work-support or last, a cam and suitable connecting devices for operating the same, a rand feeder and fitter having an operating-cam, a nail-carrier and its operating-cam, a gang or group of reciprocating drivers, and a drive-shaft to which said parts and their operat- 130

ing-cams are connected and simultaneously driven, substantially as described.

18. The combination, in a rand-attaching machine, of the work-support A, the cam a^3 upon the vertical shaft a^9 , the toggle-head a^3 , toggle a^4 , and lever a^5 , the templet B, having the rand-forming surface b^2 and holes b , the rand carrier and fitter, and the cam d^6 , for operating the same, carried upon the vertical shaft a^9 , the nail-carrier E and its cam e' , carried by the vertical shaft a^9 , the head F, the gang or group of drivers supported thereby, the cams $f^2 f^3$, for moving said head, their shaft f^6 , the said vertical shaft a^9 , and the

bevel-gears $f^{11} f^{12}$, as and for the purposes described. 15

19. The herein-described method of forming rands and attaching them to outsoles, consisting in contacting the heel end of an outsole against a former, as set forth, to provide an exposed space between the parts, forming and firmly holding the rand on the exposed surface and securing the same to the outsole, as set forth. 20
